HAND SAW CONSTRUCTION

Raymond C. Dreier, Chicago, Ill., assignor to Dreier Brothers, Inc., Chicago, Ill.

Filed Apr. 26, 1973, Ser. No. 354,513

Term of patent 14 years

Int. Cl. D8—03

U.S. Cl. D8—96

FIG. 1

FIG. 2

FIG. 3

FIG. 4

FIG. 5

FIG. 1 is a side elevational view of a hand saw construction incorporating my new design with a blade shown in broken line for illustrative purposes only;

FIG. 2 is a top elevational view of the hand saw construction of FIG. 1;

FIG. 3 is a bottom elevational view of the hand saw construction of FIG. 1;

FIG. 4 is an end elevational view from the right hand side of the hand saw construction of FIG. 1; and

FIG. 5 is an end elevational view from the left hand side of the hand saw construction of FIG. 1.

I claim:

The ornamental design for hand saw construction, as shown and described.
